UNITED STATES PATENT OFFICE

VERNOR E. GREEN, OF LITTLE FALLS, NEW YORK

TAPE-CUTTING MACHINE

Application filed May 7, 1927. Serial No. 189,711.

The invention relates to a continuously operated machine for successively cutting off measured pieces of material from a long length of the same.

5 The purpose of the invention is to provide an improved machine of the class described which is simple and durable in construction and effective and rapid in operation and adapted to be used for a wide variety of purposes.

A further purpose is to provide a machine of the type described which can be readily set to cut the pieces of material in one of a considerable number of lengths and particularly to do so without having to change the feeding rolls or the gears therefor.

Another object is to combine with the main measuring and cutting mechanism means for tending to draw the length of material forward from the measuring rolls to the knife faster than said measuring rolls positively feed the material so that greater regularity and equality of the cutting and measuring operation is secured.

25 Further purposes and advantages of the machine will appear from the specification and claim herein.

Fig. 1 is a side elevation of a machine embodying this invention.

30 Fig. 2 is a vertical longitudinal sectional view through the machine, but showing certain parts in side elevation.

Fig. 3 is an end elevation of the machine as seen from the right hand end of Fig. 1.

35 Fig. 4 is a top view on a reduced scale of said machine.

Referring to the drawings in a more particular description it will be seen that the machine comprises a box-shaped frame having feet 8, base 9 and front and rear sides 10 and 11 extending up from the base with said base and sides having mounted therein the main shaft 12 and also the shafts for the other rollers and wheels hereinafter mentioned.

The main shaft 12 projects forwardly of the forward side of the machine and has fixedly secured thereto the wheel 13 which is formed with a suitable pulley face for receiving from a belt not shown power for the

operation of the device. Upon the body or disk portion 14 of this wheel there are provided a plurality of spaced holes 15 whereby one or more striker members 16 may be detachably and selectively mounted for the 55 operation of the movable knife hereinafter described. At the rear of the machine, that is to the back of the rear side 11 there is fastened to the projecting end of the main shaft a gear 17 which engages two gears 18 and 19 which are of equal size and placed at the rear ends of shafts 20 and 21 preferably about on a level with each other and diagonally above the main shaft 12. On the shaft 20 is located the first measuring and feeding 60 roll 22 and upon the shaft 21 is located the second measuring and feeding roll 23. The peripheries of these rollers 22 and 23 are roughened, preferably knurled, so as to obtain a firm and relatively positive 65 hold upon the strip 24 of tape or other material which is to be cut into desired lengths by the machine. The strip of tape passes over the top of the two feed rolls 22 and 23 and is held down into engagement with the 70 knurled surfaces of said feed rollers by pressure roll 25 located above the level of the feed rolls on shaft 26. The feed rolls 22 and 23 and the pressure roll 25 preferably extend the full width of the space between 75 the front and rear sides of the machine. For the ordinary work of cutting tape in underwear or children's waist factories these rolls may conveniently be made of a length of 80 about one and one-half inches as this provides a machine of large enough size to cut tape or similar fabric of any width required.

Where the machine is used for cutting a strip of material of greater width than this it will be obvious that the machine may be readily increased in size without departing from the spirit of my invention. The pressure roll 25 will also have its periphery knurled to aid in maintaining the positive grip of the feed and measuring rolls 22 and 23 upon the strip 85 90 95 100 of tape 24. Spring pressure is given to the shaft 26 of the pressure roll 25 through a top bearing member 27 being placed above each of the opposite ends of the shaft 26 in the vertical slot 28 and through said bear-

ing member being yieldingly pressed downward by a coiled spring 29. The upper end of said spring is held in place upon the shank of a screw 30 mounted in a bridge piece 31. 8 The main shaft 12 as the parts are seen in Figs. 1 and 2 will be rotated anticlockwise so that the two feeding and measuring rolls 22 and 23 will be rotated clockwise and so feed the strip of tape 24 from the left to the 10 right through the machine.

As close as practicable to the right hand end of the machine there will be mounted in the chamber of the machine the auxiliary or tension roller 32 on shaft 33 driven through 15 a gear wheel 34 on the rear of said shaft 33 engaging a gear 35 mounted upon the shaft 21 to the rear of the gear 19 on 21. The gear 35 is considerably larger than the gear 34 so that this tension roller 32 will be rotated 20 appreciably faster than the main feeding and measuring rolls 22 and 23. The face of said roller 32 will be roughened slightly by transverse shallow grooves so as to effect a fair contact with the strip of material 24 but 25 preferably will not be knurled or roughened as much as the measuring and feeding rolls so that the constant slipping of this tensioning roll upon the strip of material will not injure or tear the material.

30 As the parts are assembled in the machine this tensioning roll 32 is mounted to the right of the last measuring roll and diagonally thereabove so as to bear down upon the upper surface of the strip of material 24 after it 35 comes from the last measuring roll 23. In order to obtain the necessary yielding tension between this roll and the strip of material there is placed in the machine a flat plate 36 extending from the surface of the 40 roll 23 to the fixed knife 37 mounted at the right hand end of the machine and below the strip of material 24. This plate 36 is yieldingly pressed upward by means of coiled spring 38 encircling a pin 39 projecting up 45 from the base 9 of the machine. Closely above the line of travel of the strip of material there is provided a guide plate 40 extending from the tensioning roll 32 to the movable knife 41. This movable knife is 50 mounted in the right hand end of the machine in suitable guideways so as to be capable of making a vertical reciprocating motion. Suitably and adjustably fastened to the knife 41 there is provided the knife holder 55 42 having a lug 43 projecting to the right from said knife holder. Pivoted to this lug is a swinging link 44 to which is pivotally attached the rearward end of the arm 45 on the operating lever 46.

60 This operating lever 46 is pivotally mounted on a pin 47 projecting from the near side of the machine to the left of the knife 41. Yielding tension means are connected to this lever to normally hold the movable knife 65 raised from the fixed knife 37. Such yield-

ing means may conveniently consist of a coiled spring 48 extending from a screw 49 on the base 9 of the machine to a screw 50 inserted in the lever 46 some distance to the left of the pin 47 of said lever. The left hand end of the operating lever 46 extends past the rim of wheel 14 to the inside thereof and has a downward extension 51 terminating in a short lower face 52. This face 52 in the normal or raised position of the movable 70 knife 41 is in the path of the strikers 16 located on the body 14 of the wheel 13. As any one of the striker members 16 comes up into engagement with the face 52 the left hand end of the operating lever will be quickly 75 raised thus depressing the knife with a quick shearing action against the strip of material 24 passing across the path of said knife. As the face 52, however, is very short said face is almost instantly released from the advancing 80 striker member 16 so that the knife is very quickly raised again from the path of the strip of material due to the action of the spring 48. The cutting action and the raising again of the knife is so rapid that the strip of material while constantly fed forward is so soon free to pass the line of the movable knife that no interruption of the feeding action is had. The flat spring 36 and the guide member 40 with the assistance 85 of the tensioning roll 32 all aid to push the end of the strip past the path of the moving knife as soon as that knife is removed.

If it is desired to cut the strips of material up to the limit allowed by the machine 100 only one striker member 16 is used. If the shorter lengths are to be cut the next variation is to place two of the striker members 16 in two equally spaced holes 15, that is half way around the body 14 of the wheel 13. 105 Holes are further provided spaced apart one hundred and twenty degrees or one-third of the circle thus allowing the total length of material fed forward by one rotation of the main shaft to be cut into three equal pieces. 110 If it is desired to cut the material into still shorter strips four striker members 16 are used ninety degrees apart. It will be understood that the striker members may be readily inserted or removed from the wheel 115 13 to make any of the selective lengths within the limit of the machine.

The machine is not limited to cutting tape or other selvaged material but may be used 120 to cut off pieces from a long strip of fabric having raw or cut edges. In many cases such non-selvaged strips can be used effectively by turning over one or both edges of the material in a suitable folding device placed just before the cutting machine. The fabric 125 so folded over passes into and through the machine and is cut off the same tape and the fold or folds are preserved sufficiently to allow the pieces to be used as so folded. 130

What is claimed as new and desired to be secured by Letters Patent is:

In a continuously operating machine for cutting off lengths of tape or like material, the combination of a main shaft, a measuring and feeding roll positively driven from said main shaft and adapted to positively engage and continuously feed forward a length of material, a rotatable pressure roll adapted 5 to hold the material in contact with said feeding and measuring roll, a knife located after the measuring roll and mounted for vertical sliding movement and adapted to descend across the path of the advancing material 10 and cut the same, a wheel fixed upon said main shaft and carrying a striker, a pivoted lever operatively connected to said movable knife and adapted to be operated by the striker and a drawing roll yieldingly engaging the material after said feeding and measuring roll operatively connected to said main driving shaft to be driven faster than said main feeding and measuring roll whereby 15 said drawing roll tends to draw the material faster than supplied by said main feeding and measuring roll whereby the knife has a positive-power cutting motion and a spring for withdrawing the knife after each cutting operation.

30 In witness whereof I have affixed my signature, this 16th day of April, 1927.
